UNITED STATES PATENT OFFICE.

LEO BORGER, OF NEW YORK, N. Y.

ECONOMIC AUTOMATIC STRIPPER FOR STEAM-LAUNDRY PURPOSES.

1,282,741.

Specification of Letters Patent. Patented Oct. 29, 1918.

Application filed February 6, 1918. Serial No. 215,722.

To all whom it may concern:

Be it known that I, LEO BORGER, a resident of New York, county of New York, and State of New York, have invented certain new and useful Improvements in Economic Automatic Strippers for Steam-Laundry Purposes, of which the following is a specification.

This invention relates to improvements in apparatus used in steam laundries and particularly to types of apparatus known as driers.

The principal object of the invention is to provide an apparatus comprising a chain or the like adapted to move sinuously through a heated compartment or drying chamber, means being provided on the traveling element to which the goods, as the articles laundried, may be readily attached.

20 A further object is to provide means which automatically detach the articles, permitting them to drop and be deposited in a suitable container, the act of detachment being accomplished without damage to the goods.

A still further object is to provide a detaching means which acts automatically, so that when the articles are thoroughly dried they are removed from the traveling chain without manual labor on the part of the operator.

These and other like objects are attained by the novel construction and combination of parts hereinafter described and shown in the accompanying drawings, forming a material part of this disclosure, and in which—

Figure 1 is a fragmentary side elevational view indicating the application of the invention, parts being broken away in order to disclose the interior.

Fig. 2 is a transverse sectional view taken on line 2—2 of Fig. 1, and

Fig. 3 is a vertical sectional view taken on line 3—3 of Fig. 2.

45 In the drying room suspended by brackets (not shown) is a hollow, substantially rectangular structure 10, the side walls of which are curved inwardly and upwardly at their lower edge, forming trackways 11, receptive of the trolley wheels 12, arranged in pairs upon a spindle 14, having engaged at their center brackets 15, the pendant arms 16 of which are attached at spaced intervals with the links 18 of a chain driven by any 55 convenient means (not shown) both chain

and trackway being arranged in the common manner.

On the lower sides of the chain 18, are arms 20, formed with hubs 21, with which may be engaged various article holding devices, the lower end of the arms being formed with lateral branches 22, in which are secured upturned, hook-shaped wires 23, upon which may be attached the articles of clothing to be dried as the collars indicated.

The entire construction described is of the customary type and it is to be understood that the articles to be disposed upon the chains, by whatever means may be employed, are caused to circulate through the drying 70 room until devoid of moisture and in condition for further finishing processes, such as ironing and the like.

Engaged with the track 10, is a U shaped bracket 25, clamp screws 26, being provided at its upper end, the same being adapted to draw integrally formed flanges 27, tightly against the lower outer side of the track elements 11, so as to clamp the bracket at any desired point therewith.

A pair of longitudinally opposed guides 28, are secured by the screws 29, in the lower depending elements of the U shaped bracket the same being adapted to guide the arms 20, as they are passed therethrough and prevent 85 them from moving laterally into an undesirable position.

Also intimately formed with the brackets 25, are opposed outstanding flanges or ledges 30, in which are secured by the clamp nuts 90 31, a pair of pendant rods 32, connected at their lower ends by a bar 33, held in position by nuts 34, so that the rods 32, are held in parallelism.

Slidably engaged upon the rods 32 are sleeves 35, formed with an integral connecting plate 36, its upper surface having secured to it one of the elements 38, of a hinge the other element 39 of which has attached to it a curved flat apron plate 40, having 100 near its upper edge recesses 41, beyond which extend prongs 42.

This hinged apron plate, which acts as an ejector with relation to the goods disposed upon the chain, is held in a normally erect position by means of flat springs 44, the same being bent at a right angle and secured below the connecting plate 36, as is also a stop plate 46 adjustably secured by bolt 47, whereby the apron plate 40 is prevented 110

from turning outwardly upon its hinged joint.

In order to hold the plate 36 at a suitable height and yet permit the same to recede 5 when brought in contact with the articles suspended on the chain, there are interposed between the lower end of the sleeves 35 and the nuts 34, helically coiled compression springs 48, encircling the lower ends of 10 the rods 32, thus permitting the plate 36 to be moved down under the impact of the article and be immediately returned to its operative position.

In operation, it is customary to run the 15 chain 18, outward through a suitable opening formed in the partition wall of the drying chamber, so as to permit an operator to attach garments or other articles, which have been laundered and are in a wet condition, 20 to the hooks 23, one after another in regular succession, it being understood that the chain moves at a moderate rate of speed.

When the dried articles are brought out 25 of the drying chamber, suspended on the hooks, they are caused to engage with the prongs 42 or the apron plate 40, the recesses 41 of which are adjusted to come into intimate relation but avoid contact with the hook support 22, in such manner as to detach 30 the articles suspended thereon, permitting them to fall into a basket or other suitable container.

It will be understood that due to the resilience of the plate 40, injury to the articles 35 is entirely obviated, the upper contacting edge of the apron plate moving slightly upon receiving the impact of the article, due to the resilience of the springs 44, while at the same time should an undue stress be 40 laid upon the plate it can move downwardly against the coiled springs 48, thereby assuring that no damage will be done to the goods.

By applying this stripper it releases the 45 strain from the chain which means more life to the chain and less trouble, it does not break the castings on which it hangs, it strips the collar with ease and does not tear the button holes in the collars, for it has a 50 double action, saving the hooks from break-

ing and bending and holding the collars on shirts in a firm position.

Having thus described my invention what I claim as new and desire to secure by Letters Patent, is—

1. In a drying machine, the combination with a trackway having trolley wheels engaged therewith, a chain suspended by said trolley wheels, pivoted arms formed with said chain at spaced intervals therealong, 60 and hooks carried by said arms adapted to receive articles of clothing, of a bracket secured to said trackway, guides fixed on said bracket through which said arms pass and are prevented from lateral movement, a pair 65 of spaced parallel bars engaged in said bracket, a plate slidably engaged on said bars, spring supports for said plate, an ejector plate hingedly engaged with said slidable plate, means for preventing said ejector 70 plate from turning outwardly, means adapted to normally maintain said ejector plate in position, and means formed on said ejector plate adapted to contact with articles on said suspending means whereby 75 they are disengaged therefrom.

2. In a drying machine, the combination with a movable carrier, a fixed bracket through which said carrier passes, opposed parallel rods secured in said bracket, means 80 at the lower ends of said rods whereby they are held parallel, a pair of sleeves slidable on said rods, a rigid plate integrally formed therewith, springs interposed between the lower ends of said sleeves and said connecting means, a hinge having one of its elements mounted on the upper side of said plate, a curved ejecting plate mounted on the other element of said hinges, a stop plate preventing said ejecting plate from 85 moving outwardly, springs adapted to hold said ejecting plate in a normally erect position, and means formed upon the upper edge of said ejecting plate adapted to make contact with articles disposed on said chain 90 whereby they are released therefrom.

In testimony whereof I have affixed my signature.

LEO BORGER.
